DISTRIBUTOR HEAD

Application filed April 10, 1931. Serial No. 529,050.

This invention relates to a distributor head whereby liquid in a finely divided form is discharged into a room, a tank, or the like which is on fire.

5 An object of our invention is to provide a distributor head which will discharge a stream of liquid substantially horizontally and also downwardly at an angle, thus the entire area is covered both immediately adjacent the head and at a considerable distance therefrom.

Another object is to provide a distributor head which is simple in construction, inexpensive to manufacture, and effective in use.

15 Other objects, advantages, and features of invention may appear from the accompanying drawing, the subjoined detailed description, and the appended claims.

In the drawing

20 Figure 1 is a front elevation of our distributor head.

Figure 2 is a side elevation of the head shown in Fig. 1, the lower half being in section.

25 Figure 3 is a bottom plan view, half in section, of the distributor head.

Referring more particularly to the drawing, our distributor head 1 comprises a body 2 which includes a base plate or flange 3 integral therewith so that the distributor head may be secured to the inner face of a tank containing oil, or the like, or to a wall, or any suitable face to which a liquid outlet extends. The front wall 4 of the body is arcuate 35 in shape so that water or the like is distributed in a horizontal plane over the entire area adjacent to the wall, or the like, to which the head is secured.

The wall 4 is formed of two angular faces 40 in which a plurality of ducts or ports 5 are arranged. These ports converge so that the liquid streams passing therethrough will impinge upon each other and cause a fine fog or mist which spreads over the surface of the oil in the tank, or passes into the room to effectively extinguish a fire. Due to the arcuate shape of the distributor head, the streams which pass into the tank or room are in the shape of a fan or a segment of a circle, thus 45 effectively covering the area in the tank or

room on both sides as well as in front of the distributor head.

A pair of arcuate ribs 6-7 are integrally formed with the body 2, and these ribs are positioned above and below the ports 5 for the purpose of more effectively directing the mist or fog horizontally into the tank or the room. A deflecting rib 8 extends inwardly from the front wall 4 for the purpose of deflecting the liquid both upwardly and downwardly into the ports 5.

Stepped back from the front face 4, and positioned below said face, we provide a second ring distributor 9. This ring or hollow circular body depends from the body 2 and its purpose is to distribute a mist or fog immediately adjacent to the head, both below and slightly to the front and rear in that area which is not touched by the mist from the ports 5. A plurality of converging ports 10 are provided in the body 9 through which liquid streams pass, as will be evident. A baffle plate 11 is detachably secured to the bottom of the circular body 9 by means of a screw 12.

It will be evident from the foregoing description that we have provided a distributor head which not only covers a large arcuate area around the head, but also covers the area immediately below and adjacent to the head. 80 This last feature is very vital in oil tanks in which the fire at the edge of the tank, immediately below the head must also be extinguished or the entire body of oil will again start to burn.

Having described our invention, we claim:

1. A distributor head comprising a unitary structure having a liquid chamber therein, said head having an arcuate face provided with a set of related converging ports to deliver a horizontal spray therefrom, and a second set of related ports under the first named set of ports arranged to discharge a spray downwardly and outwardly from said head.

2. A distributor head comprising a unitary structure having a liquid chamber therein, said head having an arcuate face provided with a set of related converging ports to deliver a horizontal spray therefrom, and a sec-

ond set of related ports under the first named set of ports arranged to discharge a spray downwardly and outwardly from said head, said head having a flange extending inwardly into the chamber between the related ports of the first named set of ports.

3. A distributor head comprising a unitary structure having: a base plate; a body extending horizontally from said base plate having a liquid chamber therein, said body terminating in an arcuate shaped discharge nozzle having a horizontally disposed V-shaped groove formed therein with corresponding outlet ports arranged to discharge a horizontal fan shaped spray, and said body having a second set of outlet ports angularly disposed with respect to each other to discharge a spray downwardly and outwardly from said head.

10 20 In testimony whereof, we affix our signatures.

CLAUD H. BILLS.
GLENN G. GRISWOLD.
